UNITED STATES PATENT OFFICE.

THEODORE F. KRONLUND, OF TACOMA, WASHINGTON, ASSIGNOR OF ONE-HALF TO
ALBERT ABERS, OF TACOMA, WASHINGTON.

WASTE-RECOVERING DEVICE FOR USE IN MAKING MATTRESSES.

1,366,390.

Specification of Letters Patent. Patented Jan. 25, 1921.

Application filed March 5, 1919. Serial No. 280,835.

To all whom it may concern:

Be it known that I, THEODORE F. KRONLUND, a citizen of the United States, and resident of the city of Tacoma, county of Pierce, and State of Washington, have invented certain new and useful improvements in Waste-Recovering Devices for Use in Making Mattresses, of which the following is a specification.

10 My invention consists of an apparatus for use in connection with machines such as the felting machines which are used in preparing cotton, wool and other fiber for use in making mattresses.

15 The object of my invention is two-fold,—first to avoid scattering the dust raised in operating upon such material throughout the spaces occupied by the workmen, and second to save a considerable percentage of 20 valuable fiber which otherwise would be wasted.

In the accompanying drawings, I have shown diagrammatically the apparatus which I employ in carrying out my invention. This shows the arrangement which I now prefer to use.

The figure of drawing shows the various pieces of apparatus employed and their relationship to each other.

30 In the preparation of cotton, wool, jute and other fiber, for such purposes as the making of mattresses, the material is run into a picker and from there to a felting or carding machine. This latter machine in 35 particular, produces a large amount of dust, in which is also mingled small portions of fiber which would be of value if properly used.

It is the object of my invention to remove 40 and discharge this dust to such a point where it will be unobjectionable and to save the valuable fiber masses.

In the drawing, 1 represents a machine which is known as a picker and 2 a machine 45 which is known as a carder or felter. The material is removed from the picker through a pipe 10 by means of a suction fan 11. From the suction fan 11 this material is conveyed by air through a pipe 12, which dis- 50 charges into a bin 3 and this discharges by a chute, as 30, into the felting or carding machine 2. So far as the operating parts

go, this latter machine is of a commercial type, both in construction and operation. Under ordinary circumstances it produces a 55 large amount of dust and considerable percentage of fiber is also discharged and wasted. This is objectionable for the reason that it is hard to obtain labor to work around such a machine under these conditions and, in addition, there is a considerable loss of material.

To obviate this, I have placed a hood 4 so as to cover the working parts of this machine. This is of a pyramidal shape and 65 has the small end upward, this end being connected with the suction pipe 45 which leads to a suction fan 33. The sides of this hood are preferably hinged along the line 40, so that any one of the sides may be 70 raised as desired. This hood serves to carry away from the machine the larger part of the dust which is made by the operation of the machine upon the material.

Beneath the operating parts of the machine I have installed hoods 5. Two such hoods are shown in connection with the machine illustrated, this being a machine having two main rolls. The number of these hoods would correspond with the number of 80 main rolls employed. These hoods connect through pipes 50 with a main pipe 51 which leads to the exhaust fan 33. These lower hoods convey away the particles of fiber which would otherwise fall upon the floor 85 and be scattered in the vicinity of the machine.

The suction fan 33 discharges through a pipe 34 into a dust separator 6. This dust separator is of a commercial type of construction which discharges the air and the fine dust through a central pipe 60 while the heavier particles of the fiber drop to the bottom and are discharged through pipe 61 to the picker and from there are passed to 90 the bin 3 and into the felting machine or carder 2.

With the above apparatus I have eliminated the trouble from the dust getting into the working room and also save substantially all of the fiber which otherwise would be wasted. I have, therefore, improved the working conditions and have saved material.

What I claim as my invention is:

The combination with a felting machine of a suction hood placed over the working parts, a suction hood placed beneath each of the felting rolls, a suction fan connected to draw from both upper and lower hoods, a dust separator to which the material drawn off is delivered, a picker from which the

good fiber of said material is delivered from the dust separator by gravity, and suction operated means for returning said material 10 from the picker to the felter.

Signed at Tacoma, Washington, this 26th day of February, 1919.

THEODORE F. KRONLUND.
